UNITED STATES PATENT OFFICE

JOHN H. LEHENNEY, OF LEOMINSTER, MASSACHUSETTS, ASSIGNOR TO DUPONT VISCO-
LOID COMPANY, OF WILMINGTON, DELAWARE, A CORPORATION OF DELAWARE

DESIGN FOR A WHISTLE

Application filed August 13, 1932. Serial No. 44,602. Term of patent 3½ years.

To all whom it may concern:

Be it known that I, JOHN H. LEHENNEY, a citizen of the United States, residing at Leominster, in the county of Worcester and State of Massachusetts, have invented a new, original, and ornamental Design for a Whistle, of which the following is a specification, reference being had to the accompanying drawing, forming part thereof.

Fig. 1 is a front elevation;

Fig. 2 is a rear elevation;

Fig. 3 is a plan as indicated by the arrow 3 in Fig. 1, showing my new design.

I claim:

The ornamental design for a whistle as shown.

JOHN H. LEHENNEY.
